UNITED STATES PATENT OFFICE.

JOSEPH W. BLANCHARD, ALFRED J. SCHNEEMAN, AND LOUIS A. MINEA, OF ST. PAUL,
MINNESOTA; SAID SCHNEEMAN ASSIGNOR TO SAID BLANCHARD AND SAID MINEA.

TOY.

1,301,537.

Specification of Letters Patent. Patented Apr. 22, 1919.

Application filed May 17, 1917. Serial No. 169,354.

To all whom it may concern:

Be it known that we, JOSEPH W. BLANCHARD, ALFRED J. SCHNEEMAN, and LOUIS A. MINEA, citizens of the United States, residing at St. Paul, in the county of Ramsey and State of Minnesota, have invented a new and useful Improvement in Toys, of which the following is a specification.

Our invention relates to a toy which has for its object to provide a device to simulate a portion of a locomotive and give a choo-choo noise for the amusement of the child operating the same.

The primary object is in a device of simple construction inexpensive to manufacture and attractive in appearance.

A further object is in a device having a driving element which is painted to simulate a locomotive counter-balanced wheel on both sides and still is formed of a solid disk. The driving element or wheel is connected by a connecting rod to a cross head and the cross head in turn is connected to an air cylinder.

It is also an object to provide a device which can be pushed about by a child from place to place, the whistle operating automatically by the driving wheel to simulate the choo-choo noise of a locomotive.

In the drawing forming part of this specification,

Figure 1 is a side elevation of our device. Fig. 2 is a plan view of Fig. 1.

Fig. 3 is a plan of a detail portion of the device.

Fig. 4 is a side elevation of the part illustrated in Fig. 3.

Figs. 5 and 6 are details of the shaft and crank arm.

Fig. 7 is a detail of a portion of the device taken on the line 7—7 of Fig. 1.

Fig. 8 is a detailed cross section of a portion taken on the line 8—8 of Fig. 3.

Figs. 9, 10, 11, 12 and 13 are details of the air cylinder and whistle.

Fig. 14 is a perspective of a portion of the device.

Figs. 15 and 16 illustrate sectional views of guide ways and cross heads used in our device.

Fig. 17 is a side elevation of an alternative construction.

Fig. 18 is a plan view of Fig. 17.

Fig. 19 illustrates a sectional view of the guides and cross head used in Figs. 17 and 18.

In the drawing, A represents a toy device 55 for simulating a locomotive driving wheel having a driving element B which is pivotally secured to the frame C by means of the bracket arms 1. The arms 1 are formed of thin sheet material and are formed with an embossed rib 2 which extends about the entire edge of the arms or brackets 1 forming stiffening and strengthening means for the same.

The rear end of the arms 1 are rigidly secured to the frame member C by means of bolts 3 and the forward end is formed with an opening 4 having an inwardly projecting bearing surface 5 which is adapted to be freely journaled on the surfaces 7 on the end of the axle 8. The rib 2 also extends around the opening 4 thus forming a stiffening means and giving a wide bearing surface 5.

The axle 8 is adapted to be rigidly held 75 against rotation in the driving element or wheel B by means of the semi-circular key 9 which is formed integral on the axle 8. The axle 8 is forced into an opening formed in the axis of the driving element B so as to 80 rigidly hold the axle in the wheel B. The bearing surfaces formed on either end of the axle 8 are of a smaller diameter than the body portion of the axle. The axle 8 is also formed with reduced cylindrical portions 10 85 on either end which project from the portions 7. Crank arms 11 are adapted to be swaged on to the portions 10 and center-punched at 12 so as to rigidly connect the crank arms to the axle 8.

The crank arms are preferably secured to either end of the axle so that their free ends 13 extend at right angles to each other. The arms 1 are adapted to extend on either side of the wheel B to form a bifurcated support 95 and the bearing surfaces 5 formed in the forward end of the same are held in position on the portions 7 of the axle 8 by means of the shoulder 14 and the inner surface of the crank arms 11, there being sufficient play to 100 allow the wheel B to rotate freely on the bearings 5. The arms 1 are adapted to hold the frame element C in line centrally with the longitudinal center line of the wheel B.

The wheel or driving element B is formed 105 of a solid piece of material and its side faces painted to simulate a locomotive counter-balanced drive wheel with spokes 15 and

counter-balanced portion 16. Thus the wheel or driving element C appears as a locomotive driver.

Connecting rods 17 are pivotally connected by means of the bolts 18 to the free ends of the crank arms 11 on one end and the other end of the connecting rod 17 is pivotally connected at 19 to the cross heads 20. The cross heads 20 are adapted to slide in the guide ways 21 which are formed with grooves 22 and which are secured to the top and bottom of the frame element C by means of the screws 23. Air cylinders 24 are secured to either side of the rear end of the frame element C by means of the straps 25 and lip 26 and have their piston 27 connected to the cross heads 20 by means of the connecting rod 28, which is pivotally secured to the cross heads by means of the screws 29. The pistons 27 are of ordinary construction having a plunger formed of leather or any other suitable material. The forward end 30 of the cylinder 24 being open and the rear end having an air whistle or sound making element 31 formed thereon.

The element or whistle 31 is formed by cylindrical cup members 32 and 33, the member 33 telescoping into the member 32. An annular flange 34 formed on the member 33 is adapted to space the cups 32 and 33 apart to form a chamber 35 and the flange 36 formed on the member 32, is adapted to extend over the end of the cylinder 24 and is held in position by means of the solder 37.

Holes 38 are formed in the center of the cups 32 and 33 so that air can be drawn into the cylinder 24 and forced out by the piston or plunger 27. As the air passes through the holes 38, a choo-choo or whistling noise will be made. By changing the shape and size of the cups and holes the noise can be changed.

A handle portion 39 is formed on the end of the frame element C by which the device can be engaged when it is operated.

In operation, the child or user will engage the handle 39 and push the device along rotating the driving element or wheel B and operating the connecting rod 17, cross heads 20 and pistons 27, thereby drawing air into and forcing it out through the openings 38 of the cylinders 24 to form a choo-choo noise to simulate the noise of a locomotive. The connecting rods or arms 17 are stenciled or painted so as to appear similar to the connecting arms of a locomotive. The crank arms are off-set from each other and oscillate the arms back and forth in operation, to give a similar action to that of the connecting rods on a locomotive. Thus a child can enjoy a good deal of amusement with the device A without having to make the choo-choo noise himself which if continued, becomes very tiresome.

Where two cylinders 24 and connecting

rods 17 with cross heads 20 and crank arms 11 are used, the wheel B is easily operated and well balanced. It is obvious that the cross heads 20 can be in either form illustrated in Figs. 15 and 16. In Fig. 15, 70 grooves 40 are formed in the center of the cross heads and in Fig. 16, a groove 41 is formed along the edge of the cross head.

In the alternative construction illustrated in Figs. 17 and 18, the driving element or 75 wheel B is similar to that illustrated in the preferred construction and is freely journaled to the frame element C by means of the screw 42. The wheel B being held along side of the member C and spaced from the 80 same by means of a washer 43. A washer 44 is adapted to take the wear of the head 45 of the screw 42 off the wheel and the screw 42 is held rigidly in the member C so that the wheel B will rotate freely. One connecting rod 17 is used in the construction 85 illustrated in Figs. 17 and 18 and the cross head 20 is connected in a similar manner as is illustrated in Fig. 1.

In this construction, only one air cylinder 90 24 is used and the piston rod of the same is connected to the inner surface of the cross head 20 by means of a screw 46. In the operation of this construction, the handle 39 is engaged and the wheel rotated as the device A is pushed along, thereby reciprocating the piston in the cylinder 24 and operating the air whistle 31 to give a choo-choo noise.

In playing with the device A, the same is 100 so easily operated that a child can hold the handle 39 and push or draw the device along without much effort, or the device can be carried in a convenient manner and used when desired. It is obvious that the construction can be changed and the sound 105 making element can be constructed in various manners so as to give a sharp whistle or other desired noises.

In accordance with the patent statutes 110 we have described the principles of operation of our invention together with the apparatus which we now consider to represent the best embodiment thereof, but we desire to have it understood that the construction is only illustrative and that the invention can be carried out by other means and applied to uses other than those above set forth within the scope of the following claims:

1. In a toy having a frame with a handle formed on one end, arms formed of thin sheet material rigidly fixed to and projecting in a longitudinal direction from the other end of said frame, said arms being 115 spaced apart, a wheel pivotally held between said arms and extending in close proximity to the forward end of said frame, cross head guides secured to the top and bottom edges of said frame and extending 120 125 130

from the same, cross heads adapted to be slidably held in said cross head guides, cylinders having air whistles secured to said frame and connected to said cross heads and means connecting said cross heads with said wheel 5 to reciprocate said cross heads and operate said whistles when said wheel is rotated.

2. In a toy comprising, a frame, a wheel freely mounted on the forward end of said frame, cross head guides secured to the upper and lower surfaces of said frame and extending transversely flush with said upper and lower surfaces to form a broad faced guide-way, a cross head slidably held in said 10 guide-way, a cylinder having an air whistle, secured to said frame and connected to said cross head, and means connecting said cross head with said wheel to reciprocate said cross head and operate said whistle when 15 said wheel is rotated.

Copies of this patent may be obtained for five cents each, by addressing the "Commissioner of Patents, Washington, D. C."

3. In a device of the class described comprising, a frame, arms rigidly fixed and extending from the forward end of said frame, said arms being formed of thin sheet material forming a bifurcated support, a reinforcing rib formed about the periphery of said arms forming a strengthening means therein, a bearing formed in the forward end of said arms, a wheel freely journaled in said bearing, sound making elements secured 25 to said frame, cross head guides having a broad faced guiding surface, cross heads slidably held by said guides and means for connecting said sound making elements to said wheel to operate the same when said 30 wheel is rotated for the purposes specified.

JOSEPH W. BLANCHARD.
ALFRED J. SCHNEEMAN.
